UNITED STATES PATENT OFFICE.

HENRY O. SCHMIDT, OF NEW YORK, N. Y., ASSIGNOR TO SIMONS BROTHERS & CO., OF PHILADELPHIA, PENNSYLVANIA.

DESIGN FOR A CANE OR UMBRELLA HANDLE.

SPECIFICATION forming part of Design No. 20,550, dated March 3, 1891.

Application filed February 6, 1891. Serial No. 380,509. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the shank, and extends upwardly in two cross-pieces B and C, the former of which 15 constitutes an extended crook, while the latter forms a rearwardly-extending point. The crook B has its end ornamented on the top by a series of parallel ribs F and on the bottom by the ornamental work E. The rearwardly-extending point C has upon its upper 20 surface the flower ornamentation F. The

shank A is ornamented by a series of grooves G, formed in loops about its side adjacent to the crook B, and also a series of grooves H upon the other side. The space between the 25 series of different loops or grooves may be roughened. The bottom of the shank A is finished by an annular band D.

The handle may be made of any suitable material.

Having now described my design, what I claim as new, and desire to secure by Letters Patent, is—

The design for cane or umbrella handles, substantially as described and shown. 35

In testimony of which invention I have hereunto set my hand.

HENRY O. SCHMIDT.
